(57) **CLAIM**

The ornamental design for a billiard rack, as shown and described.

DESCRIPTION

FIG. 1 is a top, front, right side perspective view showing my new design for a billiard rack.

FIG. 2 is a top view thereof.

FIG. 3 is a back view thereof.

FIG. 4 is a right side view thereof, the left side being a mirror image.

FIG. 5 is a front view thereof.

FIG. 6 is a bottom view thereof.

FIG. 7 is a bottom, front, left side perspective view thereof; and,

FIG. 8 is a cross-sectional view along lines **8-8** of FIG. 1. The broken lines that depict notch marks along the top edges of the billiard rack in FIGS. 1 and 2 indicate unclaimed portions and form no part of the claimed design.

1 Claim, 6 Drawing Sheets

FIG. 1

FIG. 2

FIG. 3

FIG. 4

FIG. 5

FIG. 6

FIG. 7

FIG. 8
